ELECTRODE FOR ELECTRON DISCHARGE DEVICES

Walter Louis Krahl, Montclair, N. J., assignor, by mesne assignments, to Arcturus Development Company, Newark, N. J., a corporation of Delaware

Application February 12, 1931. Serial No. 515,226

10 Claims. (Cl. 250—27.5)

This invention relates to electrodes for electron discharge devices and more particularly to the cathode and heater type therefor.

It is a recognized fact that in heater type of 5 electron discharge devices that improved results are obtained by connecting the cathode to the mid-point of the filament. This connection is usually accomplished by providing a center tap to the secondary of the filament transformer 10 and connecting this point to the cathode terminal of the tube socket, or by connecting a center tapped resistor across the secondary of the filament transformer and providing a conductor between the cathode terminal of the tube socket 15 and center point of the resistor.

One of the principal objects of the invention is to eliminate the necessity for center tapping or providing a potentiometer across the secondary of the filament transformer.

20 Other objects of the invention are to obtain a positive flow of the filament current in a portion of the cathode; to avoid bending the filament wire further than a right-angle bend; to utilize filament wire of less length than required for 25 hair-pin filaments; to enable the filament to be readily assembled in the cathode; to secure simplicity of construction and operation; and to obtain other advantages and results as may be brought out in the following description.

30 Referring to the accompanying drawing in which like numerals of reference indicate same parts throughout the several views:

Fig. 1 is an elevation of an electron discharge device showing my invention applied thereto, the 35 side of the anode nearest the observer being omitted so as to show the parts normally within the anode;

Fig. 2 is a vertical longitudinal section over the cathode showing the same on a larger scale than 40 illustrated in Fig. 1;

Fig. 3 is a plan or end view of the cathode and filament taken on line 3—3 of Fig. 2, looking in the direction of the arrows;

Fig. 4 is an elevation of a modified construction 45 of cathode with filament thereon; and

Fig. 5 is a longitudinal sectional view on line 5—5 of Fig. 4.

In the specific embodiment of the invention 50 illustrated in said drawing, reference numeral 1 indicates an envelope as ordinarily used in connection with electron discharge devices, the same being carried by a base 2 and having a stem 3 at the base end of the envelope extending upwardly within the same. A plurality of support wires are sealed in the upper end of the press 3

projecting upwardly therefrom and carry an anode 4, grid 5, cathode 6 and filament 7 as will be understood by those versed in the art. Certain of the supports are connected to suitable prongs in the base so as to obtain electrical connection from the outside of the device to the electrodes therein. As here shown, a prong 8 connects with a support 9 carrying the anode. Another prong 10 is connected to a support 11 for the grid. Two other prongs, 12 and 13, are 60 electrically connected to the lower ends of the filament 7 projecting from the bottom of the cathode which is connected to prong 14.

As more particularly shown in Figs. 2 and 3, the filament 7 is preferably formed from two lengths 70 of wire which extend through the cathode properly insulated therefrom and from each other by proper spacing or insulative coating, or otherwise as well known in the art. The sections of the filament thus formed are preferably of equal resistance. At the upper end of the cathode are 75 preferably provided laterally extending ears 16, 17, shown as formed integrally with the cathode and bent radially outward from the end of said cathode, one ear preferably being diametrically opposite from the other ear. The upper end of each length of the filament 7 is also bent laterally and one of these bent ends 18 is attached to one ear 16, while the other bent end 19 is attached to the other ear 17. Attachment of the bent ends 80 to said ears is accomplished in any desired manner, as by welding. It will be observed that by bending the ears outwardly and bending the ends of the filament sections outwardly the same are readily accessible for welding purposes. It will 85 furthermore be observed that a circuit is thus obtained from one prong 12 through support 12', to one section of the filament 7 up to its bent end 18 to ears 16 and then through the material forming the cathode to the other ear 17 and bent end 90 19 on the other filament section. The circuit then is completed through that section of the filament 7 to its support 15 and connected prong 13.

The construction described above accordingly 95 obtains a mid-point connection for the filament wherein the filament circuit must of necessity pass through a portion of the cathode and will therefore unfailingly obtain equal potential of the cathode and filament at the mid-point. In the manufacture of the tube, no further test is necessary than to see that the filament will glow in order to determine if there is contact between the mid-point of the filament and the cathode, since the filament cannot glow unless there is such contact of both sections with the cathode. As- 105 110

sembly of the device is likewise very simple in that the filament sections can be dropped into the cathode very readily independent of each other and without any tendency to rub against the inside of the cathode under tension as often occurs with hair-pin filament. This assumes importance where the filament and cathode are protected from each other by an insulative coating, as the frictional contact under tension may suffice to expose 10 the bare metal and result in a short circuit sooner or later.

In Figs. 4 and 5, a modified construction of cathode is illustrated, the same having ears 20, 21 upstanding from the end thereof instead of bending outwardly, said ears receiving the bent ends 15 of the filament sections transversely thereof, as clearly shown in Fig. 4. The bent ends 18, 19 in this construction are welded or otherwise secured to the ears where they cross the same, and thus obtain positive contact for completing the 20 filament circuit through a portion of the cathode. In these two figures now being described, the further feature is illustrated of increasing the path 25 of the filament current in the cathode by slotting the cathode as at 22 in a longitudinal plan transverse to the plan of the filament sections. By this construction one of the ears 20, projects 30 from one of the bifurcations of the cathode while the other ear 21 projects from the other bifurcation. The slot 22 may be made of any desired 35 depth, that is, may bifurcate the cathode for such portions of its length as found desirable. In the present instance the slot is shown as substantially three-quarters of the length of the cathode, thus requiring the filament current to pass 40 down the one bifurcation to the bottom of the slot and then up the other bifurcation in order to complete the circuit from the one filament section to the other. This construction will accordingly obtain as nearly constant an equalization 45 of the potential between the mid-point of the filament and the cathode as ordinarily required for electron discharge devices.

Obviously detail changes and modifications may 45 be made in the construction and use of my improved electron device without departing from the spirit or scope of the invention, and I do not 50 wish to be understood as limiting myself to the exact construction shown or described except as set forth in the following claims when construed in the light of the prior art.

What I claim is:

1. In combination with a tubular cathode, a 55 filament for heating said cathode, said filament comprising a plurality of sections having ends

thereof connected at separated points to the cathode, said cathode enclosing said filament sections.

2. In combination with a tubular cathode, a 80 filament for heating said cathode, said filament comprising a plurality of sections, each section having one end thereof secured to the cathode with the ends of the sections mechanically separate so as to complete the electric circuit through a portion of the cathode, said cathode enclosing 85 said filament sections.

3. In combination with a cathode having separated ears thereon, of a filament connected to said ears.

4. In combination with a cathode having separated ears thereon, a filament comprising sections, each section being secured individually to an ear. 90

5. In combination with a cathode having separated ears thereon, a filament comprising sections, each section being secured individually to an ear, the cathode forming an electrical path 95 completing the electric circuit from one filament section to another.

6. In combination with a cathode, ears on the 100 cathode projecting therefrom, and filament sections each having bent ends engaging said ears for obtaining an electrical connection from each filament section to the cathode.

7. In combination with a cathode, ears on the 105 cathode projecting radially outward therefrom, and filament sections each having bent ends engaging said ears for obtaining an electrical connection 110 from each filament section to the cathode.

8. In combination with a cathode, ears on the 115 cathode projecting longitudinally therefrom, and filament sections each having bent ends engaging said ears for obtaining an electrical connection 120 from each filament section to the cathode.

9. In combination with a cathode, ears on the 125 cathode projecting therefrom, and filament sections each having bent ends engaging said ears for obtaining an electrical connection from each filament section to the cathode, said cathode having a portion of itself bifurcated with one of said ears on each bifurcation.

10. In combination with a cathode, ears on the 130 cathode projecting longitudinally therefrom, and filament sections each having bent ends engaging said ears for obtaining an electrical connection 135 from each filament section to the cathode, said cathode having a portion of itself bifurcated with one of said ears on each bifurcation.
